2,378,275

BUILDING CONSTRUCTION

Russell Barr Williamson, Milwaukee, Wis., assignor to Percy H. Waller, Wilmette, Ill., and to Charles C. Kirk, Western Springs, Ill.

Application August 23, 1943, Serial No. 499,625

5 Claims. (Cl. 20—2)

The present invention relates to prefabricated housing constructions and is particularly directed to roofing, siding and floor constructions that facilitate rapid mass prefabrication with features that make assembly on the site an operation that can be carried out with speed and ease.

One principal purpose of the invention is to provide a panel construction for the side walls and roofs that give strength and rigidity to the construction with a minimum amount of material. The panel construction is such that the load bearing studs for the walls are stiffened and braced by the panels while they also serve as the means for connecting two adjacent panels.

A further and more detailed object of the invention is the provision of a novel joint construction between adjacent panel sections of a roof whereby the joint between adjacent sections is adequately sealed by overlapping of the roof material at the joint above the level of the intermediate portions of the roofing material.

It is also a purpose of the invention to provide a panel construction for buildings wherein the panels themselves embody all of the necessary building openings such as windows and doors so that the window and door constructions can be fitted together at the factory and shipped out as completed panels for erection on the site.

The features and advantages of the invention will appear more fully as the description proceeds reference being had to the accompanying drawings wherein a preferred form of the invention is shown. It should be understood however that the drawings and description are illustrative only and should not be taken as limiting the invention except insofar as it is limited by the claims.

In the drawings:

Fig. 1 is a fragmentary sectional view through a building showing my improved roof section, side wall section and floor section as actually applied;

Fig. 2 is a view in side elevation of a plain side wall section frame previous to the application of the inner and outer wall surfaces thereto;

Fig. 3 is a view similar to Fig. 2 showing a like frame for a door before the application of the surface materials thereto;

Fig. 4 is a sectional view taken horizontally through a completed door frame section as installed in a wall, the section being taken substantially on the line 4—4 of Fig. 3;

Fig. 5 is a perspective view illustrating the supporting construction utilized for a side wall, this supporting construction being the part which receives and is braced by the side wall panels;

Fig. 6 is a sectional view taken on the line 6—6 of Fig. 2 but showing the completed panel with the inner and outer sheets in place;

Fig. 7 is a plan view, with parts broken away, of a completed roof section;

Fig. 8 is a fragmentary perspective view illustrating two adjacent roof sections before being placed together, one of the roof sections being sectioned along one edge to illustrate the various elements that comprise the roof section;

Fig. 9 is a fragmentary sectional view taken adjacent the corner of a building and illustrating the manner of finishing off the end of a roof panel;

Fig. 10 is an enlarged fragmentary sectional view taken on the line 10—10 of Fig. 1;

Fig. 11 is a plan view, with parts broken away, illustrating a floor section;

Fig. 12 is an enlarged fragmentary section taken on the line 12—12 of Fig. 1;

Fig. 13 is a perspective view of one of the connecting elements utilized in joining the floor sections together.

Referring now in detail to the drawings, there is shown in Fig. 1 a fragmentary section through a building, the section being sufficiently enlarged to include a side wall portion 10, a roof portion 11 and a floor portion 12 of the building. The building is mounted upon a suitable foundation comprising a base 13 which may be a continuous concrete wall or a series of posts as desired. Upon the base 13 at the exterior wall of the building I provide a sill 14 and intermediate the outer walls I provide piers 15 on which main supporting floor sills 16 rest. The floor sills of the building of the type shown in Fig. 1 preferably are made of 2 inch by 10 inch timbers. Immediately inside the sills 14 and on the opposite sides of the sills 16 I provide floor supporting structural members 17 and 18. Preferably the members 17 are of slightly less depth than the members 18 so as to give the floor a slope outwardly toward the outer wall.

The floor sections 12, as illustrated best in Figs. 1 and 10 to 12, inclusive, comprise rectangular frameworks made up of a plurality of frame members 22 and 22a which are connected together at the ends by two boards 23 and which are braced intermediate their ends by cross bracing members 24. The top surface of the floor section comprises a $\frac{1}{2}$ inch panel 25 preferably of plywood, the under surface of which is coated with asphalt or a similar material. The panels 25 project over the frame members along one side and one end. Insulating pads 26 are secured to the under surface of the panels 25 and may be of any desired

thickness depending upon the degree of insulation necessary.

The floor sections 12 rest upon the members 17 and 18 and are fastened together. The floor section fastening is illustrated in Fig. 11. Two adjacent sections are nailed by nails 20 to a relatively thick section side frame member 22a, the adjacent floor section having its top panel 25 extending beyond its side frame member 22 for this purpose. The frame members are also 10 locked together by special dowel pins 19 and wedges 21. The dowel pins 19 which fasten two adjacent floor sections together may be left out where the floor is too close to the ground to permit their installation. The floor sections are fastened to the sills 16 by nails 20 going through the panels 25 into the sills 16. As shown in Figs. 11 and 12, the dowels 19 pass through two adjacent members 22-22a of the floor and are provided with reduced neck portions 27 and 28 to receive the wedges 21. The dowels 19 may be constructed of any suitable tough material such as maple, and likewise the wedges which are slightly tapered from the slotted end portion 29 thereof to the solid end portion 30. An elongated slot 31 in the wedge is flared as indicated at 32 to facilitate application of the wedge 21 to the dowel pin 19.

The assembly of the floor section of the building is believed to be evident from the foregoing description. Briefly it comprises placing the sills 14 and 16 in place and securing the floor supporting members 17 and 18 after which the floor panels 12 are laid in side by side and fastened by means of the nails 20 and the dowel pins 19. If the dowels 19 are used the nailing of adjacent floor sections to each other may be dispensed with although it is preferable to use both nails and dowels. When the floor is laid an outer finishing strip or skirting board 33 is applied around the building and a water table strip 34 is secured to the sills 14 immediately above the skirting board 33.

Referring now to the side walls 10, the construction of the side walls comprises initially a side frame such as is illustrated in Fig. 5. This side frame comprises a base strip 35, studding 36 and a roof supporting girder 37. The upper and lower ends of the studding 36 are notched to receive the strip 35 and the girder 37. However, the notches at the upper ends of the studding are substantially less than the depth of the girder 37 and the girder itself is notched as indicated at 38 so as to interlock with the studding. The top of the ends of the studding and the girder 37 provide a support and locating means for a strip 39 that is provided on each roof section as will be presently explained. The side frame thus constructed provides the supporting and mounting structure for several panels 40 to complete the side wall 10 of the building. These panels 40 are made up individually as shown in Figs. 2 to 4, inclusive, and may be plain sections, door sections or window sections as desired, the panels themselves being interchangeable with respect to the frame shown in Fig. 5. This interchangeability is determined by the construction of the panels and the studding 36, the outer faces of the studding 36 being cut as indicated at 41 and 42 so as to provide a reduced rib 43 that fits between two adjacent panels which are then nailed by nails 44 to the studding as illustrated in Fig. 4.

Each plain panel 40 is composed of a rectangular frame-work as illustrated in Fig. 2, the frame being composed of $\frac{3}{4}$ inch strips 45 forming the

periphery of the section and intermediate cross strips 46 and 46a. On the outer or exposed surface I provide a $\frac{1}{2}$ inch sheet 47 which desirably may be of a pressed fibre construction or plywood properly treated to protect it. The inner surfaces of the frame members 45, 46 and 46a are covered by a sheet 48 of gypsum board, plywood or the equivalent. It will be noted from an examination of Fig. 6 that the side edges of the inner sheet 48 are cut back from the strips 45 so as to leave approximately half of the strip edge exposed. The side edges of the outer sheet are cut back also to allow the nails 44 to be driven between adjacent members 45 which they hold by engagement of the heads of the nails. The crack is filled with a suitable caulking material. The panels 40 are accurately constructed in prefabrication so that when they are placed in position between the studding 36 the side edges of the sheet 48 abut the ridges 43 on the studding and the strips 45 overlap the ridges 43 on the studding so that they can be nailed to the studding. This overlapped construction makes use of the panels 40 as a bracing means for the studding since the panels themselves are rigid because of the framework therein and the covering sheets 47 and 48. The caulking shows as a vertical line every four feet, which is the standard width of a panel. Where a door or window section is embodied, as shown in Fig. 4, the construction remains the same except that the additional width necessary to complete the four foot panel about the door or window frame is built up as illustrated in Figs. 3 and 4. The panels 40 as shown extend the full height of the side frame shown in Fig. 5 and overlap the girder 37 so they may be secured thereto. Likewise the girder 37 is set back so as to align vertically with the panels 40. The panels themselves rest directly upon the sills 14 and carry no weight other than their own weight. Desirably the spaces between the frame members 45 and 46 of the panels may be filled with insulation 49.

Referring now to the roof section construction, this construction is illustrated best in Figs. 1 and 6 to 9, inclusive. Each roof section comprises a framework and a covering. The framework includes a plurality of longitudinally running boards 50 which are of greater depth at the peak of the roof than at the outside wall. As an example, the boards 50 are approximately $7\frac{1}{2}$ inches wide at one end and $4\frac{1}{2}$ inches wide at the other end and 1 inch thick. These boards comprise the rafters and they are connected together by a suitable sheathing such as plywood sheathing 51 on the top and a gypsum board sheathing 52 or its equivalent on the bottom. Cross bracing is provided by staggered cross strips 53 at intervals lengthwise of the boards 50. Insulation 54 is provided between the sheets 51 and 52. At the upper or deeper end of the roof section the boards 50 are connected by two vertically spaced cross pieces 55. The ends of the boards 50 are notched as shown in Fig. 7 so that a projecting tongue 50a on each board extends between the upper and lower cross pieces 55.

The roof is supported at the center by beams 56 that run lengthwise of the building and provide adequate support for the roof. These beams are preferably supported at their opposite ends and at intervals by posts indicated at 57. The posts and beams provide roof support and also serve with the roof sections as the means for vertically positioning the side walls as will be explained hereinafter.

The roof section is provided along its side edges and its upper edge with beveled cleats 58 and 59, these cleats terminating flush with the surfaces of the outer boards 50 and the pieces 55. Over the top of the cleats and over the top of the sheathing I provide a two-ply fabricated roofing 60 of an asphalt and fibre composition. This roofing is fastened down to the plywood sheathing 51 by means of asphalt cement. At one side edge the roofing extends over the beveled strip 58 as indicated at 61 and at the top edge, as indicated at 62, the roofing extends over the beveled strip 59. After the roofing section is prefabricated this extended part of the prefabricated roofing is bent down and fastened by a lathe strip until the roof section is put in place. When the roof section is put in place the loose flap of the fabricated roofing is overlapped over the adjacent beveled strip and fastened down by cementing and nailing. A cover flashing 63 is then put over both beveled strips and cemented down to complete the roof joints. This construction is shown in detail in Fig. 9. There is a flashing strip 63 along the ridge of the roof as well as along the joints between laterally adjacent roof sections.

Each roof section is provided with two cross strips 39. One strip is fastened to the boards 50 adjacent to the shallower end of the section but spaced therefrom and is adapted to serve as a stop against which the member 37 is fastened. The other strip 39 is fastened to the boards 50 adjacent to the deeper end of the roof section but is set back just the width of a beam 56. In the final erection the two adjacent strips 39 are fastened to the beams 56 and to each other by bolts 64 (see Fig. 1) or any other suitable fastening means.

The cross strips 53 are provided with openings 65 which are screened as shown at 66 in the strips 53 closest to the shallower ends of the roof sections. The purpose of these openings and the spacing of the strips 55 is to provide ventilation throughout the roof sections above the pads 54 of insulation. This built-in ventilation feature is of considerable value in keeping down heat transfer downwardly through the roof. The shallower ends of the roof sections are provided with end boards 67 which slope as shown. The asphalt roofing sheet extends over the board 67 and is turned down and fastened to the outer surface of the end board. In the erection, when several sections of the roof have been laid together a finishing plate 68 is nailed to the end boards and completely covers the joints between end boards of adjacent sections giving a good appearance and securing the sections in line at their outer ends.

The end roof sections are slightly wider than the intermediate panels so as to extend over the end walls of the building. The construction of the body of the end sections of the roof is the same as that of the other sections except that one side is extended and constructed as shown in Fig. 8. An additional board 50c is laid against the outer board 50 of a regular section and another wider board 50b is spaced slightly from it. An anchor strip 69 is provided. This strip extends between the strips 39 and serves as a stop for the member 37 of an end wall 10a that is made just like the side walls. The asphalt covering and the top panel of the end section of the roof are extended and finished off as shown in Fig. 8. A stop strip 70 is applied after erection between

the end wall 10a and the lower end of the board 50b.

In erection the floors are first laid after the sills 14 and 16 and the members 17 and 18 are placed on the posts 13 and 15. Next the posts 57 and the beams 56 are erected and secured in vertical alignment. This is the only vertical alignment necessary as the side and end walls are "locked" to the center construction by the roof sections. This is accomplished in the following manner. A side wall unit can be completed on the floor by attaching the side wall panels to the frame shown in Fig. 5. This unit is then set on the sill 14 and raised and temporarily held by braces to the center posts 57. The roof sections are then laid on and fastened to the beams 56. When this is done the side wall units are pushed against the outer strips 39 and a lock strip 71 (see Fig. 1) is nailed to

20 the roof section against the outer surface of the side wall. When the side walls are thus fastened the end walls which overlap them can readily be set up in place and the corner is closed by two vertical boards (not shown) at right angles to each other which overlap each other on the outside of the corner and are nailed together.

25 Inner wall panels may of course be provided for partitions. These panels are constructed in essentially the same fashion as the side wall panels but they have the same finish on both sides.

30 From the foregoing description it is believed that the nature of my invention and the advantages thereof will be readily apparent to those skilled in the art.

35 Having thus described my invention, what I claim as new and desire to secure by Letters Patent is:

1. In a building structure the combination of a central framework including upright posts and beams on top thereof with side wall units and roof sections, said side wall units comprising a plurality of complete sections, a framework including studs connecting said sections together and a top girder cooperating with said beam to support the roof sections, the said roof sections having framework attaching strips thereon secured to the beams and other attaching strips thereon engaging said girder whereby to position it upright in proper spaced relation to the beams, and a locking strip outside the wall sections secured to the roof sections and holding said girder against the adjacent strips on the roof sections, said locking strip extending across a plurality of the roof sections whereby it also interconnects 55 the roof sections to each other.

2. In a building structure the combination of a row of central posts and beams thereon, end walls comprising frames having top girders and studs, certain of said studs aligning vertically with 60 said beams, side walls having studs and top girders and roof sections having securing strips thereon, said roof sections being arranged in opposing pairs with their adjacent ends resting on said beams and the adjacent securing strips being secured to the beams to prevent separation of one roof section from its paired section, said roof sections having positioning strips against which the girders of the end and side walls rest, and locking strips secured to the roof sections and 65 overlapping the outer surfaces of the side and end walls to lock them in place.

3. In a building structure a side wall unit comprising a plurality of panels with like exterior dimensions, each panel having an inner and outer 70 sheet covering and a framework, the periphery

of which projects beyond the inner sheet covering at the opposite side edges, a load supporting frame comprising upright studs, a top girder, and a bottom tie plate, said studs having reduced sections extending between the adjacent edges of the inner sheets of two abutting panels, the said panels being secured to the studs and the girder and tie plate.

4. In a building structure a side wall unit comprising a plurality of panels with like exterior dimensions, each panel having an inner and outer sheet covering and a framework, the periphery of which projects beyond the inner sheet covering at the opposite side edges, a load supporting frame comprising upright studs, a top girder, and a bottom tie plate, said studs having reduced sections extending between the adjacent edges of the inner sheets of two abutting panels, the said panels being secured to the studs and the girder

and tie plate, certain of said panels including door frames.

5. In a building structure the combination of a floor comprising sills and duplicate floor sections interconnected with each other and resting on said sills, a central supporting and aligning structure comprising spaced posts resting on said floor, a beam connecting the top of said posts, 10 side wall units composed of a load carrying side wall frame and panels attached thereto, and roof sections attached to said beam and having means to secure the top portions of said side wall units in spaced relation to the beam, said roof sections comprising tapered rafters, a top covering for said rafters, a bottom sheet for said rafters, and cross braces between said rafters, the said cross braces having apertures whereby to provide ventilation in said roof sections.

RUSSELL BARR WILLIAMSON.
